Serial No. 647,858

5 Claims. (Cl. 122—20)

Our invention relates to hot water heaters and has particular reference to heaters embodying heating coils or similar containers supported inside of furnaces.

Ordinary furnaces for heating houses are usually provided with devices for heating water for household purposes. These devices are placed in the path of hot products of combustion absorbing some of their heat, causing clinkers, and in 10 no way assisting in the process of combustion itself. The average efficiency of such hand fired furnaces is usually rather low due to the irregular burning of the coal spread on the grate bars, there being a tendency for the draft to blow holes 15 through the layer of coal, especially in the center of the grate. As a result, the coal layer around the edges of the grate where it lies near the walls of the boiler becomes cooler, with corresponding loss of the furnace efficiency. A large 20 proportion of the available heat is therefore wasted, although some of it is used for heating pipes or coils with water. Direct contact with hot gases is, however, injurious to such water heating devices, causing their oxidation, clogging with 25 soot, and forming hard scale inside.

In order to obviate these difficulties, we provide a special housing for the water heating coil so that the coil is protected from direct action of the products of combustion, and, therefore, no clinkers can be formed. The housing itself we utilize 30 as a means for improving the combustion and raising the furnace efficiency. For this purpose we make the housing in the shape of a cylinder closed on top where the heating coil is located, 35 and open at the bottom, being suspended at a certain distance above the grate bars. The sides of the cylinder below the coil are provided with numerous apertures for air passing from the grate into the furnace.

The housing is placed in the middle of the grate so that a circular or tubular space is formed 40 between its walls and the inside walls of the furnace. Coal is piled in this space up to the top of the cylinder and is burned in the draft of air passing from the bottom, partly through the grate, partly through the holes in the cylinder. We provide the cylinder with an arrangement for turning 45 it around so as to rake the coal. We obtain therefore a greatly increased combustion space and a large area in direct contact with the boiler walls where the heat is needed most. Coal can be loaded into the combustion space without 50 any regard for its accurate spreading, and lower 55 grades of coal can be successfully burned with

our device. The very position of this device does away with the needless waste of coal.

Our invention is more fully described in the accompanying specification and drawings in which—

Fig. 1 is a sectional elevation of our generator mounted in the furnace of a heating boiler, Fig. 2 is an outside view of the device in a different furnace and Fig. 3 is a section on the line 3—3 of Fig. 1.

Our generator consists of a coil 1 with intake and outlet pipes 2 and 3 fitted in a cover block 4. The pipes are supported in the walls of a boiler 5 and extend to the top and bottom of a hot water tank 6. The latter is shown mounted on 70 legs 7 although it may be supported in any ordinary manner for instance, against the wall of a house. The block 4 has a flange 8 on which a corresponding flange of a tubular housing 9 rests. The housing has a lug 10 with a hole which can 75 be engaged by a hook 11 for turning the housing on its seat on the flange 8. The housing is suspended on the pipes 2 and 3 in the middle of the boiler 5.

The housing is open at the bottom and is placed 80 at a short distance above the grate bars 12. Its walls are provided with longitudinal slots 13 terminating below the coil 1 so that a hot air pocket is formed around the coil in the upper portion 85 of the housing. The slots have converging or tapering sides forming air nozzles for the draft of air flowing through the grate bars and from inside of the housing into the coal 14 piled in the tubular space between the housing and the walls of the boiler 5. With this arrangement the 90 coal may be charged into the furnace without any regard to its even spreading, and it will burn evenly around the housing without formation of the blown-through holes and dead spots like in ordinary furnaces. The grate bars can be shaken 95 in the ordinary manner for loosening coal and dropping the ashes. The housing can be turned by the hook 11 for breaking slag, loosening coal and permitting the ashes to fall through the slots 13.

The housing may be cast from a heat resisting ferro-alloy such as nichrome or manganese steel. Our generator can be used with any suitable furnace with grate bars 12 or 23 for coal or similar hard fuel, for boilers of low or high pressure as shown in Fig. 1, or for hot air or similar furnaces as shown in Fig. 2. It improves the efficiency of the furnace by adding an increased surface of combustion around the housing, its slots serving as an additional grate; the slots 110

being vertical, the removal of ashes is made easier, and a more economical combustion process can be carried on with even a low grade fuel in the vertical cylindrical space surrounding the housing. Fuel in this space remains in close contact with the inside walls of the furnace thereby maintaining them at a high temperature, which is especially important when these walls form a part of the boiler. At the same time the generator itself provides a very efficient means for supplying hot water with the low fuel consumption. The coil is well protected from direct contact with the hot products of combustion and is thereby protected from their oxidizing action, from soot and other particles, from the burning action of the flame, and, also, from the formation of clinkers.

We claim as our invention:

1. In a water heater, the combination with a block, of a heating coil supported under said block, pipes extending from said coil through said block, said pipes being adapted to support said block with said coil in the middle of a furnace, a tubular housing open at the bottom rotatively supported on said block and enclosing said coil, the walls of said housing below said coil being provided with a plurality of apertures for air, and means to rotate said housing on said block for raking the coal piled in said furnace around said housing.
2. In a water heater, the combination with a block, of a heating member supported on the under side of said block, intake and exhaust pipes extending from said member through said block and passing through the wall of a furnace, and a tubular housing enclosing said member and rotatively supported on said block, the lower end of said housing being open, said pipes being adapted to support said block with said member and said housing in said furnace at a distance above the grate bars of said furnace, the walls of said housing being provided with a plurality of apertures for air passing from said grate bars to the coal piled around said housing.

3. In a water heater, the combination with a block, of a container for water supported under said block, intake and exhaust pipes extending from said container through said block, and a tubular housing enclosing said container and rotatively supported on said block, the lower end of said housing being open, said housing with said container being adapted to be supported in a furnace above the grate bars, the walls of said housing being provided with apertures converging to the outside and forming nozzles for the air passing from said grates to the coal outside of said housing.

4. In a water heater, the combination with a container for water, pipes extending from said container and adapted to support said container in a furnace, a tubular housing enclosing said container and arranged to be rotated on said container, the lower end of said housing being open and placed above the grate bars of said furnace, the walls of said container being provided with a plurality of apertures, and projections on the outside of said housing for raking coal piled around said housing when the latter is rotated.

5. In a water heater, the combination with a container for water, of a tubular housing rotatively supported with its upper portion on said container and forming a hot air pocket around said container, the lower end of said housing being open, the walls of said housing below said container being provided with a plurality of apertures, and pipes extending from said container and adapted to support said container with said housing in the middle of a furnace with the lower edge of said housing at a distance above the grate of said furnace, said housing being adapted to stir and to rake the coal piled in said furnace on said grate around said housing.
